UNITED STATES PATENT OFFICE

2,366,288

INTERNAL-COMBUSTION ENGINE

Clifford R. Rogers, Oak Park, Ill., assignor to International Harvester Company, a corporation of New Jersey

Application January 13, 1941, Serial No. 374,185

6 Claims. (Cl. 123—32)

This invention relates to an internal combustion engine, and more particularly to a control means for regulating the operation of an internal combustion engine.

Certain aspects and combinations of the invention are particularly adapted for use in engines of the solid injection type, and particularly in engines of that type incorporating therein a gasoline starting arrangement.

In a particular type of internal combustion engine well known to those skilled in the art, the engine is adapted to be started on volatile mixture and, after a sufficient warming-up period, to be operated on Diesel fuel. In one form of such engine, the gasoline and Diesel fuel operation takes place in the same engine; that is to say, the head of the engine is provided with auxiliary compression chambers for lowering the compression ratio during operation on volatile mixture. The release of compression is taken care of by compression release valves establishing communication between main compression chambers and auxiliary compression chambers, at the same time exposing spark plugs in the latter chambers. When the compression release valves are opened for the purpose of operating the engine on volatile mixture, it is necessary that the supply of solid fuel be cut off. For this purpose, the compression release valves, the fuel supply means, and the engine ignition means are interconnected, so that the change over from volatile mixture to solid fuel may be made in one simple operation.

The principal object of the present invention is to provide improved control means particularly adapted for use in conjunction with an engine of the type referred to, and specifically for the purpose of controlling the change over from one fuel to another.

An important object is to provide a speed control means embodying an over-center device capable of locking the means in a predetermined position. In this aspect of the invention, this particular means is capable of use in any form of engine, and is not necessarily limited to use in an engine of the type referred to.

Another important object is to provide a second control means for operating the compression release valves, this means also including an over-center device.

Another object is to make provision for the interconnection of these two control means in an engine of the type referred to above, thereby providing means preventing the premature opera-

tion of one means until the engine is ready for the fuel change-over.

Certain other objects and desirable features of the invention may be appreciated from the following detailed description taken in conjunction with the accompanying sheets of drawings, in which:

Figure 1 is a side elevational view of the invention as disclosed in conjunction with an engine forming part of a tractor of the track-laying type;

Figure 2 is an enlarged elevational view of a portion of the structure shown in Figure 1, showing the parts in other positions;

Figure 3 is an enlarged sectional view taken substantially on the line 3—3 of Figure 1; and,

Figure 4 is a detail view of the rocker arm construction for operating the compression release valves.

The invention is embodied in but one of many forms which it may assume. For the purposes of disclosure, an engine, generally indicated at 10, is shown as the power plant of a tractor of the track-laying type, the tractor being generally of the conventional construction and including a body 11 having a radiator 12, hood structure 13, dash panel 14, and operator's station 15. The remainder of the structure is sufficiently illustrated and requires no further description.

As best shown in Figure 1, the engine 10 comprises the conventional block structure 16, head 17, and valve cover 18. The engine is of the four-cylinder type, and includes four fuel injection nozzles 19 for supplying fuel to the cylinders. The nozzles 19 are supplied with fuel through fuel lines 20 connected to fuel outlets 21 for a fuel injection pump 22. This pump is of the governed type and may assume the form of that construction illustrated in the patent to A. Schnurle et al., No. 2,096,203, issued October 19, 1937, on application Serial No. 741,302, filed August 24, 1934. Reference to the structure illustrated in that patent is invited for the purpose of clarifying the details of the structure and operation of the pump.

Further description of the pump is omitted, except in so far as the operation thereof is necessary to a disclosure of the present invention.

The injection pump is supplied with fuel through a fuel inlet 23, which communicates with a fuel supply valve 24. Rotation of the valve 24 regulates the supply of fuel to the engine. The valve 24 comprises the upper end of a rotatable shaft 25, which has its lower end provided as a pinion 26. This pinion is engaged by a longitudinally movable rack 27. The rack is connected by

a link 28 to a governor construction, which may be of the type illustrated in the patent referred to above. The link 28 is connected by a tension spring 29 to the upper end of an arm 30 rigidly carried by a transverse rock-shaft 31 journaled in the body of the pump 22. The shaft 31 carries, outside the pump, an operating arm 32 for adjusting the tension on the spring 29. The parts, as shown in Figure 1, are in open position, so that the engine will receive maximum supply of fuel; that is to say, the arm 32 is in its rearwardmost position, so that the greatest tension is placed on the spring 29, thus holding the rack 27 in position to hold the valve 24 in maximum open position. Movement of the rack 27 from right to left, as shown in Figure 1, rotates the valve 24 from maximum open to minimum closed position. By means of the governor, not shown, which is connected to the arm 28, the position of the valve 24 may be determined according to the speed of operation of the engine, and the operation of the governor may be further controlled by selecting different positions for the arm 32, thus adjusting the tension on the spring 29 and requiring the governor to overcome greater or less tension on the spring in order to move the arm 28 in a counter-clockwise position.

For the purpose of regulating the arm 32 from the operator's station 15, there is provided on the dash panel 14 a bracket structure 33 carrying a rock-shaft 34. A control lever 35 is pivoted on the shaft 34 and takes the form of a bell-crank having a secondary arm 36. The arm 36 has pivotally connected thereto one end of a forwardly extending link 31, the other end of which is pivotally connected to a member 38, which is in turn rockably carried on a rock-shaft 39 journaled in and extending transversely of the engine block 16. The member 38 carries a block 40 provided with a bore 41, through which is loosely passed the upper end of a link 42. The block 40 is further provided with a member 43 having opposite, longitudinally spaced, apertured end portions 44, through which the link 42 passes freely. A compression spring 45 encircles a portion of the link 42 and is interposed between one side of the block 40 and the proximate portion 44 of the member 43. A second similar spring 46 is similarly arranged at the other side of the block 40. The uppermost or rearwardmost end of the link 42 is threaded and provided with an adjusting nut 47. The other end of the link 42 is pivotally connected to the arm 32 previously referred to. It will thus be seen that, by means of the connections just described, the arm 32 of the pump 22 may be adjusted by means of the control lever 35 mounted on the dash panel 14.

As best shown in Figure 3, the engine block 16 is provided with a transverse bearing portion 48, which journals the rock-shaft 39, the shaft 39 extending at the right side of the engine, as viewed in Figure 3. The block is further provided with a number of removable cylinders, only one of which is shown at 49. The engine head 17 is provided with a main combustion chamber 50 and an auxiliary combustion chamber 51. A passage 52 connects the two chambers and is adapted to be opened or closed by the operation of a poppet valve 53. This valve is carried for vertical movement in the head 17, and is provided at its upper end with an enlarged portion 54 abutted by a compression spring 55 normally retaining the valve 53 in closed position. The enlarged, upper end of the valve 53 is engaged by a roller 56 carried on a short arm 57 rigidly carried on a longi-

tudinal rock-shaft 58 journaled in the second head 18. The shaft 58 further carries for movement therewith an arm 59 extending toward the right side of the engine and provided with a socket portion engaged by the lower ball end of a short vertical link 60. The upper end of the link 60 forms a ball and socket with one end of an arm 61 rigidly carried by a short rock-shaft 62 journaled in the right side of the head 18. The connections just described provide means for operating the valve 53, so that downward pressure on the outer end of the arm 59 results in downward movement of the arm 57, thus opening the valve 53 and establishing communication between the main combustion chamber and the auxiliary combustion chamber. It will be understood that there are as many valves 53 as there are cylinders, the foregoing description relating to but a single valve and cylinder merely for the purpose of simplifying the disclosure.

According to the present invention, the operation of the valve 53 is controlled from the operator's station 15. To this end, the short rock-shaft 62 carries rigidly thereon a forwardly extending arm 63, the forward end of which is pivotally connected to the upper end of a vertical link 64. The lower end of the link 64 is pivotally connected to the forward end of a link 65, which has its rearward end rigidly secured to the transverse rock-shaft 39, the structure just described being located at the right side of the engine. The rock-shaft 39 carries rigidly thereon at the left side of the engine an upstanding arm 66, the upper end of which is pivotally connected to a rearwardly extending link 67. The rearward end of the link 67 is pivotally connected to the intermediate portion of a second control lever 68 pivoted at its lower end at 69 to the front face of the dash panel 14. The shape of the lever is disclosed in Figure 1, where it is shown that the lever has its handle portion disposed at the rear face of the dash panel and accessible, along with the control lever 35, to the operator on the operator's station 15. The front face of the panel 14 rigidly carries an ear 70, to which is connected the lower end of a tension spring 71, the upper end of which is connected to a curved link 72, which is in turn pivotally connected to an intermediate portion of the control lever 68. As best shown in Figure 2, the spring 71 and link 72 provide over-center means for retaining the control lever in position after it has been moved rearwardly. A rearward portion of the lever 68 is provided with a stop portion 73, which abuts the dash panel 14 to prevent further forward movement of the lever. When the lever 68 is in the position shown in Figure 2, the rock-shaft 39 has been rocked in a clockwise direction, as viewed in Figure 2, thus moving the arm 59 on the other end of the rock-shaft 39 upwardly. This upward movement is transmitted through the link 64 to move the arm 63 on the shaft 62 upwardly. This movement results in downward movement of the arm 57 on the inner end of the shaft 62, which movement is transmitted, through the link 60, the arms 59 and 57, and the roller 56, to the upper end of the valve 53, thus opening the valve to establish communication between the chambers 50 and 51. The engine head 17 carries a spark plug 74 extending into the chamber 51 when the valve 53 is opened. The inner end of the spark plug is exposed for ignition purposes to the main combustion chamber 50. The ignition apparatus associated with the spark plug has not been illustrated, for it forms no part of

the present invention. Likewise eliminated, is the means for supplying volatile fuel to the engine.

For the purpose of interrelating the control levers 35 and 68, means are provided to guard against premature operation of the lever 35 while the lever 68 is in rearward position, as shown in Figure 2. For this purpose, the lower end of the arm 66 on the left end of the rock-shaft 39 is provided with a depending lug 75. The member 38 includes integrally therewith an upstanding lug 76. The lugs are disposed one in the path of the other, so that the two may interengage under certain circumstances. Looking now to Figure 1, it will be seen that the lugs 75 and 76 are in maximum spaced-apart position; that is to say, the angular positions of the arm 66 and member 38 are such that the angle between the lugs 75 and 76 is substantially its maximum. The cooperation between these two lugs will be further set forth in the description of the operation of the structure.

As a further feature of the invention, there is provided means for locking the control lever 35 in a position that corresponds to a closed position of the valve 24, in which position the valve 24 cuts off the supply of solid fuel through the fuel lines 20 to the injection nozzles 19. This means assumes the form of an over-center device incorporated in the connection between the link 37 and the control lever 35. As shown in Figure 1, the lever 35 is in substantially maximum open position. The lever may have movement in a clockwise direction to adjust the arm 32 for regulating solid fuel supply. As shown in Figure 2, maximum downward movement of the lever 35 swings the arm 36 and the upper end of the link 37 to an over-center position with reference to a straight line extended through the block 40 on the member 38 and the axis of rotation of the rock-shaft 34 in the bracket 33 on the dash panel 14. It will be further noted that, during this movement, the member 38 has also been swung in a clockwise direction. When the control lever 68 is pulled rearwardly, it too is locked in position by the over-center means consisting of the spring 71 and link 72. The arm 66 is moved in a clockwise direction and the lug 75 on that arm moves forward to engage or substantially engage the lug 76 on the arm 38. Further details of the construction will be brought out in the following description of the operation of the engine and the change-over from volatile mixture to solid fuel.

As previously stated, volatile fuel is supplied to the engine in mixture form through usual fuel-supplying means, not shown. Solid fuel is supplied through the injection pump 22 described above. Since the engine must be started on volatile mixture supply, the following preliminaries are to be observed. The control lever 68 is moved rearwardly to the position shown in Figure 2. This movement results through actuation of the linkage shown in Figure 3 in movement of the compression release valves 53 to open position. Because of the establishment of communication between the chambers 51 and 50, the compression ratio is lowered considerably and the engine is now adapted to operate on volatile mixture. Before starting the engine, the control lever 35 is moved in a clockwise direction until it becomes locked in position, as shown in Figure 2. In this position, the linkage, including the links 37 and 42, is moved forwardly, thus moving the arm 32 on the injection pump 22 in a counter-clockwise

direction until it assumes the position shown in Figure 2. Upon the occurrence of this movement, the rack 27 moves forwardly and rotates the valve 24 to cut off completely the supply of solid fuel to the cylinders 49. It will be understood, of course, that a simultaneous connection of the ignition apparatus, not shown, takes place upon the movement of the lever 68, appropriate connections being ordinarily made with the rock-shaft 39. In addition, the volatile fuel supply and manifold apparatus, not shown, are also brought into operation. Ignition and manifold devices of the type just referred to are well known in the art and need no discussion here.

With the parts in the position just described, the engine is adapted for operation on gasoline or whatever other volatile mixture that may be used. During this phase of the operation, the over-center lock for the lever 35 prevents inadvertent movement of the lever to open position, thus insuring against the accidental supply of solid fuel to the combustion chamber. When it is desired to change over to solid fuel operation, the lever 68 is first moved forwardly, thus closing the valves 53. By this movement of the lever, the compression ratio is increased, the ignition system is cut off, and the supply of volatile mixture is cut off. The lever 35 is then moved upwardly, breaking the temporary over-center lock and the engine is then ready for operation on Diesel fuel. It will be noted that in the particular instance illustrated, the lugs 75 and 76, as shown in Figure 2, are engaged. The engagement between these two lugs is further assurance against the premature movement of the control lever 35 to prevent the supply of solid fuel while the engine is operating on gasoline. The supply of solid fuel under such circumstances would have an undesirable effect on the operation of the engine and would militate against proper operation of the engine on Diesel fuel. Accordingly, the lever 35 cannot be moved upwardly as long as the lever 68 is in rearward position, this lever being temporarily locked by the over-center means provided by the link 72 and spring 71. In short, with the arm 66 in the position as set by the rearward position of the lever 68, the lug 75 is interposed in the path of rearward movement of the lug 76, which must take place when the lever 35 is moved upwardly. It will be understood, of course, that the angular relation and positions of the arm 66 and the member 38 may be altered as desired, so that, in a position of the parts comparable to that illustrated in Figure 2, there may be greater distance between the lugs 75 and 76. Under certain circumstances and according to certain adjustments of the parts, a slight movement of the lever 35 may be permitted. In any event, the cooperation between the lugs 75 and 76 guards against flooding the cylinders with Diesel fuel during operation of the engine on volatile mixture.

It will be understood that the over-center means provided for either of the control levers may be separately utilized and the employment of either or both is not to be understood as being limited by the disclosure to an engine of the particular type referred to. It will be further understood that numerous other modifications and alterations may be made in the particular embodiment of the invention as illustrated without departing from the spirit and scope of the invention as defined in the appended claims.

What is claimed is:

1. In a solid fuel injection engine having a main combustion chamber, an auxiliary combustion chamber arranged in communication with the main chamber, valve means operable selectively from open to closed position to establish or cut off communication between the chambers, and means for supplying solid fuel to one of the chambers and including a regulating element movable through a fuel-delivery range into a predetermined position to restrict the fuel supply, the combination of a rock-shaft, control means carried by the rock-shaft and connected to the regulating element and arranged for movement through a fuel delivery control range into a predetermined position corresponding to that of the regulating element, a second control means carried by the rock-shaft independently of the first control means for operating the valve means and movable through a range to establish open and closed positions of the valve means, and means interconnecting the two control means for temporarily excluding movement of the first control means from the aforesaid delivery range while the second control means establishes the open position of the valve means.
2. In an engine having communicative main and auxiliary fuel combustion chambers adapting the engine for low compression gaseous fuel operation when such chambers are in communication and for high compression solid fuel operation when such chambers are non-communicative, a valve manipulatable between opened and closed positions to respectively establish and terminate communication between said chambers, and fuel supplying means adjustable into and within a range for supplying solid fuel for the main chamber at variable rates and adjustable from said range for terminating such supply; the combination of an adjustable fuel control means operably connected with the fuel supplying means to adjust the fuel supply means into and out of said range and within said range, valve control means operably connected with said valve and adjustable independently of said fuel control means for opening and closing said valve, and interlock means operable under control of said valve control means and said fuel control means to resist adjustment of the fuel supplying means into the fuel supplying range while the valve is in the opened position.
3. The combination set forth in claim 2, wherein the interlock means is also operable under control of said valve control means and said fuel control means to resist opening of said valve while the fuel supplying means is in the fuel supplying range.
4. In an engine having communicative main and auxiliary fuel combustion chambers adapting the engine for operation on low compression fuel when such chambers are in communication and for operation on high compression fuel when such chambers are noncommunicative, a valve settable between opened and closed positions to respectively establish and terminate communication between said chambers, and fuel supply means settable into a fuel supply condition for manipulation to supply the higher compression fuel to the main chamber at variable rates and settable into a fuel cut-off condition for terminating such supply; the combination of an adjustable fuel control member adjustable to vary the amount of fuel supplied by the fuel supply means, a linkage operably connecting said member with said fuel supply means for controlling the setting thereof, a valve control member manipulatable independently of the fuel control member, a linkage operably connecting the valve control member with said valve for controlling the setting thereof, and interlock means having counterparts respectively settable under control of said linkages into position to resist setting of the fuel supply means into the fuel supply condition by adjustment of the fuel control member while the valve is closed.
5. The combination set forth in claim 4, wherein the interlock counterparts are also settable under control of said control members to resist opening of the valve by adjustment of the valve control member while the fuel supply means is set in the fuel supply adjustment.
6. In an engine having communicative main and auxiliary fuel combustion chambers adapting the engine for operation on low compression fuel when such chambers are in communication and for operation on higher compression fuel when such chambers are non-communicative, a valve manipulatable between opened and closed positions to respectively establish and terminate communication between said chambers, and fuel supply means settable to a fuel supply adjustment for supplying the high compression fuel to the main chamber at rates constituting an inverse function of engine speed and settable to a cut-off adjustment for terminating such supply; the combination of an adjustable fuel control member adjustable to vary the amount of fuel supplied by the fuel supply means, an over-center linkage operably connecting said member with said fuel supply means and settable in an over-center position precluding unseting of the fuel supply means from the fuel cut-off adjustment excepting by adjustment of the fuel control member, a valve control member connected with said valve and adjustable for opening and closing said valve, and interlock means settable under control of said control members to resist such unseting of the fuel supply means from the cut-off adjustment by adjustment of the fuel control member while the valve is in the opened position.

CLIFFORD R. ROGERS.

CERTIFICATE OF CORRECTION.

Patent No. 2,366,288.

January 2, 1945.

CLIFFORD R. ROGERS.

It is hereby certified that error appears in the printed specification of the above numbered patent requiring correction as follows: Page 4, first column, line 24, claim 1, for "means from" read --means to--; and second column, line 24, claim 4, for "closed" read --open--; and that the said Letters Patent should be read with this correction therein that the same may conform to the record of the case in the Patent Office.

Signed and sealed this 24th day of April, A. D. 1945.

Leslie Frazer
